ASH TRAY AND STAND FOR SCORE PADS

Edward W. Discher, Milwaukee, Wis.

Application March 20, 1948, Serial No. 145,254

Term of patent 14 years

(Cl. D34—5)

To all whom it may concern:

Be it known that I, Edward W. Discher, a citizen of the United States, and resident of Milwaukee, in the county of Milwaukee and State of Wisconsin, have invented a new, original, and ornamental Design for an Ash Tray and Stand for Score Pads, of which the following is a specification, reference being had to the accompanying drawing, forming part thereof.

Figure 1 is a side elevational view of the ash tray and stand for score pads, showing my new design.

Figure 2 is a front elevational view thereof.

Figure 3 is a top plan view showing more particularly the ash tray arrangement on the stand.

Figure 4 is a rear elevational view of my ash tray and stand for score pads.

Figure 5 is a bottom plan view thereof.

I claim:

The ornamental design for an ash tray and stand for score pads, as shown.

EDWARD W. DISCHER.
